SYSTEM OF CONTROL.

1,274,711.

Specification of Letters Patent. Patented Aug. 6, 1918.

Application filed May 20, 1916. Serial No. 98,785.

To all whom it may concern:

Be it known that we, RUDOLF E. HELLMUND, a subject of the Emperor of Germany, and a resident of Swissvale, in the county of Allegheny and State of Pennsylvania, RALPH E. FERRIS, a citizen of the United States, and a resident of Swissvale, in the county of Allegheny and State of Pennsylvania, and LAURENCE M. PERKINS, a citizen of the United States, and a resident of Wilkinsburg, in the county of Allegheny and State of Pennsylvania, have invented a new and useful Improvement in Systems of Control, of which the following is a specification.

Our invention relates to systems of control and especially to the regenerative operation of electric railway motors and the like.

The object of our invention is to provide a system of the above-indicated character which shall be relatively simple and inexpensive in construction and effective and reliable in operation and which shall inherently embody certain advantages and novel features, as hereinafter more specifically set forth.

In the operation of regenerative control systems, one of the first considerations is to protect the vehicle and the momentum-driven machines from injury, particularly with respect to over-speeding. Such conditions call for a system of regeneration wherein a slight rise in the speed of the vehicle causes a relatively large increase in the regenerated current, that is, in the braking effort of the vehicle. However, a system having this characteristic is not very stable, since the regenerated current is materially affected by the unavoidable fluctuations of supply-circuit voltage, which condition is liable to cause damage to the momentum-driven machines, such as over-heating, "flash-over" troubles, etc. For this reason, it is desirable to employ a system wherein the regenerated current is not very sensitive to supply-circuit voltage fluctuations, that is to say, does not vary to any great extent in accordance with such fluctuations or with slight changes of speed. The most practical system, therefore, appears to be a compromise between the above-mentioned extreme characteristics, whereby a relatively

small increase in regenerated current, as the vehicle speed increases, obtains.

The first system recited above, wherein a relatively large increase of regenerated current is produced by a slight rise in vehicle speed, may be secured by exciting the main-machine field windings from an auxiliary source of energy, such as a motor-generator set, battery, etc., the voltage of which remains substantially constant or decreases as the load thereof increases.

If the auxiliary exciting voltage is caused to rise in a materially greater ratio than does the load, then the above-mentioned second system is obtained which is unduly responsive to fluctuations in supply-circuit voltage; whereas, a relatively small increase of exciting armature voltage with the load will secure the above-mentioned desired compromise system.

Other desirable operating characteristics of the auxiliary motor-generator set that is preferably employed for main field-winding excitation purposes may be briefly stated as follows: First, the driving motor of the motor-generator set should be of the series type, whereby the speed of the auxiliary machines may vary in accordance with material changes of supply-circuit voltage and thus keep pace with the desirable main field-winding excitation under varying conditions and also whereby the motor may be relatively insusceptible to "flash-over" troubles, particularly upon the resumption of supply-circuit voltage after a temporary interruption thereof caused, for example, by the vehicle current-collecting device leaving the supply-circuit conductor. As is well-known, the series-type motor is less liable to "flash-over" difficulties than the shunt type motor, since the field-winding flux of a series machine builds up relatively rapidly under the above-mentioned conditions of a sudden resumption of supply-circuit voltage, and thus the field flux is not unduly distorted by the initial restored armature current flux and, consequently, "flash-over" conditions do not obtain. On the other hand, a shunt-excited machine produces the familiar damping or choke-coil effect in the field circuit, which leads to an undesirable predominance of restored arma-

ture-current flux over the simultaneous shunt-field-winding flux, with the consequent liability to "flash-over" difficulties.

Secondly, it is obvious that, even though the driving motor of the motor-generator set is preferably series-excited, means should be provided for preventing the motor from "running away", that is, over-speeding, without employing a shunt field winding which entails the above-mentioned undesirable tendency to "flash-over" conditions.

Thirdly, the necessary regulation of the system to compensate for the gradual decrease of vehicle speed should preferably involve the handling of relatively small auxiliary currents rather than the main regenerated current, whereby the initial cost and operating charges of the system are materially reduced. It is our aim, in the herein-after-described systems, to accomplish the above-mentioned results in as simple and inexpensive a manner as is compatible with reliable operation.

Our invention may best be understood by reference to the accompanying drawing, wherein Figure 1 is a diagrammatic view of a system of control embodying our invention; and Fig. 2 and Fig. 3 are similar diagrammatic views of modified systems constructed and arranged in accordance with the invention.

Referring to Fig. 1, the system here shown comprises a plurality of supply-circuit conductors respectively marked "Trolley" and "Ground"; a plurality of main dynamo-electric machines respectively having armature windings A^1 and A^2 and field-magnet windings F^1 and F^2 of the series type; a plurality of main-circuit resistors R^1 and R^2 that are associated with the respective main armatures in a manner to be described; and an auxiliary motor-generator set having its driving armature winding M fed from the supply circuit and its generator or exciting armature winding G connected to excite the main field windings F^1 and F^2 .

The armature windings M and G may be mechanically connected in any suitable manner, as by a shaft s . The driving armature winding M is provided with a series-connected field-magnet winding MF^1 and a second field-magnet winding MF of the series type that is energized in accordance with the regenerated current; while the exciting armature winding G is provided with a supply-circuit-excited or shunt field-magnet winding GF^1 and a second field-magnet winding GF of the series type that is connected in series relation with the field-magnet winding MF to be energized in accordance with the regenerated current.

As indicated by the positive signs and the arrows, the two field-magnet windings for the driving armature M are adapted to act cumulatively to assist the voltage of the

driving armature winding M . On the other hand, in accordance with the designation of plus and minus signs, the supply-circuit-excited field-magnet winding GF^1 is connected to assist the voltage of the exciting armature winding G , while the allied field-magnet winding GF is adapted to oppose such voltage or, in other words, the field winding GF is differentially related to the shunt field winding GF^1 , for a purpose to be described.

Inasmuch as a particular type of regenerative control system that is employed is not essential to our present invention, we have not deemed it necessary to describe, in detail, means for effecting the illustrated circuit connections or for inaugurating regenerative operation. The main-circuit connections about to be described are fully set forth and claimed in a copending application of R. E. Hellmund, Serial No. 44,443, filed August 9, 1915, and assigned to the Westinghouse Electric & Manufacturing Company.

Assuming that regenerative operation has been started and that the various circuit connections are as shown in Fig. 1, such connections may be traced as follows: One main circuit is completed from the trolley through junction-point 10, conductor 11, main armature A^1 , junction-point 12, main-circuit resistor R^1 , a switching device 13, here conventionally shown as an arrow-head, junction-point 14, conductors 15 and 16, field-magnet winding GF for the exciting armature G , conductor 17, field-magnet winding MF for the driving armature winding M and conductors 18 and 19 to the negative conductor ground.

A second similar main circuit is completed from the junction-point 10 through conductors 20 and 21, main armature A^2 , junction-point 22, main-circuit resistor R^2 , a switching device 23 that corresponds to the other switching device 13, and thence through the junction-point 14, as just recited.

One terminal 24 of the exciting armature winding G is connected through conductor 25 to the conductor 15 and junction-point 14, where the circuit divides, one branch including switching device 13, main-circuit resistor R^1 , junction-point 12, main field winding F^1 and conductor 26 to another junction-point 27; and the other branch including switching device 23, main-circuit resistor R^2 , junction-point 22, main field winding F^2 and the junction-point 27, whence circuit is completed through conductor 28 to the other terminal 29 of the exciting armature winding G .

An auxiliary circuit is completed from the conductor 20, through conductors 30 and 31, driving armature winding M of the motor-generator set, series field winding MF

for the armature winding M and conductors 32 and 19 to the negative conductor ground.

A further auxiliary circuit is completed from conductor 30 through conductor 33, 5 auxiliary resistor AR^2 , conductor 34, shunt field winding GF^1 for the exciting armature winding G and conductor 35 to the negative conductor 19. A second auxiliary resistor AR^1 is connected, in parallel relation, to the shunt field winding GF^1 and is adapted to be varied in active circuit value by means of a plurality of suitable switches 1, 2, 3 and 4.

The operation of the above-described system, in so far as it pertains to our present invention, may be set forth as follows: upon an incipient increase of regenerative current in the main momentum-driven armature A^1 , for example, a correspondingly augmented voltage drop occurs across the main-circuit resistor R^1 , whereby an accordingly reduced voltage is available for delivery to the main field winding F^1 from the approximately constant-voltage exciting armature 25 winding G . Such reduction of main field winding current, therefore, tends to restore the main armature or regenerated current to the desired normal value, and thus a substantially constant regenerated current, for 30 any given speed, is inherently maintained. Obviously, an incipient decrease of regenerated current in either main armature will effect a corresponding increase of current in the allied main field winding and thus maintain the desired conditions.

However, a further inherent regulating action occurs in the motor-generator set to aid in accomplishing the desired object. In the case of the above mentioned incipient increase of regenerated current, a corresponding increase of the current traversing the field-magnet winding GF obtains, and, by reason of the differential relation of the field-magnet windings GF and GF^1 , the resultant or 45 effective flux in the armature winding G is accordingly reduced and thus, again, a decreased current is delivered to the main field winding F^1 . The two above-mentioned regulating actions, of course, occur at a relatively rapid rate and thus the variations of the regenerated current may be maintained within desirably narrow limits.

Moreover, although no shunt field winding for the driving armature winding M is 55 provided under light-load conditions of the auxiliary machines, which entails a relatively small exciting current in the series field winding MF^1 , a sufficient current flows through the other field winding MF at all 60 times to insure a flux in the driving armature winding M of sufficient strength to prevent the armature from over-speeding. Thus, the desired result is attained without requiring the use of a shunt-field winding.

65 To regulate the system in order to com-

pensate for the gradual decrease of speed of the momentum-driven machines, the switching devices 13 and 23 may be actuated, preferably in accordance with the regenerated current, as fully described in the 70 above mentioned co-pending application of R. E. Hellmund, although such undesirable and relatively expensive main-circuit regulation may be dispensed with by suitable design of parts in our present invention. For example, the effective excitation of the shunt field winding GF^1 for the exciting armature winding G may be gradually increased by successively opening the switches 1 to 4, inclusive, as the vehicle speed 75 decreases, or the other auxiliary resistor AR^2 may be gradually excluded from circuit to perform a similar function of effecting a gradual increase of the main field-winding excitation. The two last-recited 80 methods involve the use of relatively small switching devices and the handling of slight currents and, consequently, are advantageous in these respects.

Reference may now be had to Fig. 2, 90 wherein the only difference from the system that has just been described resides in the substitution of a shunt field winding GF^2 for the supply-circuit-excited field-magnet winding GF^1 of the previous system. The 95 field winding GF^2 is connected in parallel relation to a translating device TD , such as a resistor, that is connected in series relation with the driving armature winding M . As indicated by the corresponding arrow, the 100 current in the shunt field winding GF^2 is adapted to assist the voltage of the exciting armature winding G , while the other field-magnet winding GF is again connected differentially, that is, to oppose the action of 105 the shunt-field winding GF^2 .

The general inherent regulating operation of the present system is obviously substantially like that set forth in connection with Fig. 1, and no other exposition thereof is 110 believed to be necessary here. However, a somewhat different method of compensating for the gradual decrease in speed of the momentum-driven machines is employed, such method embodying the use of a plurality of 115 suitable switches 5, 6 and 7 that are respectively adapted to short-circuit contiguous sections of the translating device TD , whereby the successive opening of such switches effects a gradual increase of the current 120 traversing the shunt field winding GF^2 to increase the voltage of the exciting armature winding G in the desired ratio for accomplishing the intended functions, as will be understood.

Referring now to Fig. 3, the main-circuit connections and the arrangement of armature and field windings of the driving motor of the motor-generator set are like those employed in the system that is illustrated in 130

Fig. 1. However, the terminal 24 of the exciting armature winding G is connected through conductor 25 to a junction-point or lower-terminal point 45 of a field-magnet winding GF³, whence circuit is completed through conductor 15, as previously described. Consequently, the field winding GF³ carries the regenerated or main-armature current as in the previous systems, and, 5 in addition, the current that is supplied by the exciting armature winding G to the main field winding F¹ and F². The supply circuit excited field-magnet winding GF¹ that is shown in Fig. 1 is again employed, being 10 connected through the auxiliary resistor AR² between the conductor 30 and the conductor 17, which is connected to the junction-point 45, and whence a common circuit is completed through field winding MF for the 15 driving armature winding M and conductors 18 and 19 to the negative conductor ground. Another auxiliary resistor AR³ is connected in shunt relation to the supply-circuit-excited field-magnet winding GF¹ and is 20 adapted to be varied in active circuit value by means of a plurality of suitable switches 25 1, 2 and 3.

In the present instance, the field winding GF³ is connected to assist the voltage of the 30 exciting armature winding G, while the shunt field winding GF¹ is adapted to oppose such voltage, that is to say, the field windings GF³ and GF¹ are differentially related, as indicated by the positive and negative 35 signs and the corresponding arrows, but in the reverse manner from that employed in the system of Fig. 1.

However, the inherent regulating action 40 of the two field windings for the exciting armature winding G follows similar principles to those set forth in connection with the previous systems. Briefly, an incipient increase in the regenerated or main armature current correspondingly augments the 45 current traversing the field-magnet winding GF³, and the design of parts is such that the resultant or effective field flux that is produced by the two differentially-related field windings is accordingly reduced and 50 the desired decrease of main field-winding excitation obtains. Although such reduction of main field-winding current also influences the voltage of the driving armature winding M, it will be appreciated that this fact may 55 be taken into account in designing the motor-generator set, and the final inherent regulating result may be made to conform to the desired objects.

Regulation of the system to counteract the 60 gradual decrease in speed of the main momentum-driven machines may be effected in a manner opposite to that set forth in connection with Fig. 1, by reason of the reversed arrangement of the shunt-excited and series-excited field windings for the arma-

ture winding G, that is to say, by gradually closing the switches 1, 2 and 3 to thus correspondingly decrease the differential effect of the supply-circuit-excited field-magnet winding GF¹ and permit of the desired increase of main field-winding excitation during the gradual decrease of vehicle speed. 70

We do not wish to be restricted to the specific circuit connections or arrangement and location of parts, particularly the auxiliary 75 regulating arrangements, hereinbefore set forth, as various modifications thereof may be effected without departing from the spirit and scope of our invention. We desire, therefore, that only such limitations shall be 80 imposed as are indicated in the appended claims.

We claim as our invention:

1. In a system of control, the combination with a supply-circuit and a main dynamo-electric machine having an armature and a field winding, of a plurality of auxiliary mechanically-connected armature windings respectively driven from said supply circuit and connected to excite said field winding, a 85 plurality of differentially-related field-magnet windings for the exciting armature winding, and a plurality of cumulatively-related field-magnet windings for the driving 90 armature winding. 95

2. In a system of control, the combination with a supply-circuit and a main dynamo-electric machine having an armature and a field winding, of a plurality of auxiliary mechanically-connected armature windings 100 one of which is adapted to excite said field winding and the other for driving purposes, and a plurality of field-magnet windings of the series type for the driving auxiliary armature winding energized by different currents and mutually functioning to prevent over-speed conditions of said driving armature winding. 105

3. In a system of control, the combination with a supply-circuit and a main dynamo-electric machine having an armature and a field winding, of a plurality of auxiliary mechanically-connected armature windings respectively adapted for driving purposes and to excite said field winding, and a plurality of field-magnet windings of the series type for the driving auxiliary armature winding respectively energized by the main-armature current and the driving armature current. 110 115

4. In a system of control, the combination with a supply-circuit and a main dynamo-electric machine having an armature and a field winding, of a plurality of auxiliary mechanically-connected armature windings 125 respectively adapted for driving purposes and to excite said field winding, a plurality of field-magnet windings for the respective auxiliary armature windings energized in accordance with the main-armature current, 130

a series field-magnet winding for the driving armature winding, and a shunt-excited field-magnet winding for the exciting armature winding.

5. In a system of control, the combination with a supply-circuit and a main dynamo-electric machine having an armature and a field winding, of a plurality of auxiliary mechanically-connected armature windings respectively adapted for driving purposes and to excite said field winding, a plurality of field-magnet windings for the respective auxiliary armature windings energized in accordance with the main-armature current, 10 a series field-magnet winding for the driving armature winding adapted to aid its allied field winding, and a shunt-excited field-magnet winding for the exciting armature winding adapted to oppose its allied field winding.

- 20 6. In a system of control, the combination with a supply-circuit and a main dynamo-electric machine having an armature and a field winding, of a plurality of auxiliary mechanically-connected armature windings respectively driven from the supply circuit and connected to excite said field winding, a plurality of field-magnet windings for the respective auxiliary armature windings energized in accordance with the main-armature current and adapted to respectively assist and oppose the voltage of the auxiliary armature windings, a series field-magnet winding for the driving armature winding 25 adapted to aid its allied field winding, and a supply-circuit-excited field-magnet winding for the exciting armature winding adapted to oppose its allied field winding.

- 30 7. In a system of control, the combination with a supply-circuit and a main dynamo-electric machine having an armature and a field winding, of a plurality of auxiliary mechanically-connected armature windings respectively driven from the supply circuit 35 and connected to excite said field winding, and a plurality of field-magnet windings for the respective auxiliary armature windings energized in accordance with the main-armature current and the total main-machine current, respectively.

- 40 8. In a system of control, the combination with a supply-circuit and a main dynamo-electric machine having an armature and a field winding, of a plurality of auxiliary mechanically-connected armature windings respectively driven from the supply circuit and connected to excite said field winding, a plurality of field-magnet windings for the respective auxiliary armature windings energized in accordance with the main-armature current and the total main-machine current, respectively, a second field-magnet winding for the driving armature winding adapted to assist its allied field winding, and a second field-magnet winding for the 45

exciting armature winding adapted to oppose its allied field winding.

9. In a system of control, the combination with a supply-circuit and a main dynamo-electric machine having an armature and a field winding, of a plurality of auxiliary mechanically-connected armature windings respectively driven from the supply circuit and connected to excite said field winding, a plurality of field-magnet windings for the 50 respective auxiliary armature windings energized in accordance with the main-armature current and the total main-machine current, respectively, a series field-magnet winding for the driving armature winding adapted to assist its allied field winding, and a supply-circuit-excited field-magnet winding for the exciting armature winding adapted to oppose its allied field winding.

10. In a system of control, the combination with a supply-circuit and a main dynamo-electric machine having an armature and a field winding, of a plurality of auxiliary mechanically-connected armature windings respectively driven from said supply circuit 55 and connected to excite said field winding, a plurality of differentially-related field-magnet windings for the exciting armature winding, and a plurality of cumulatively-related field-magnet windings for the driving armature winding, and means for regulating certain of the auxiliary field windings to secure predetermined excitation of the main field winding.

11. In a system of control, the combination with a supply-circuit and a main dynamo-electric machine having an armature and a field winding, of a plurality of auxiliary mechanically-connected armature windings respectively adapted for driving purposes 60 and to excite said field winding, a plurality of field-magnet windings for the respective auxiliary armature windings energized in accordance with the main-armature current, a series field-magnet winding for the driving armature winding, and a shunt-excited field-magnet winding for the exciting armature winding, and means for varying the effect of the shunt-excited field winding to maintain a substantially constant main-armature current.

12. In a system of control, the combination with a supply-circuit and a main dynamo-electric machine having an armature and a field winding, of a plurality of auxiliary mechanically-connected armature windings respectively driven from the supply circuit and connected to excite said field winding, a plurality of field-magnet windings for the 70 respective auxiliary armature windings energized in accordance with the main-armature current and adapted to respectively assist and oppose the voltage of the auxiliary armature windings, a series field-magnet winding for the driving armature winding 75

adapted to aid its allied field winding, and a supply-circuit-excited field-magnet winding for the exciting armature winding adapted to oppose its allied field windings, and 5 means for varying the effect of the supply-circuit-excited field-winding to maintain a substantially constant main-armature current.

13. In a system of control, the combination 10 with a supply circuit and a main dynamo-electric machine having an armature and a field winding, of an auxiliary motor-generator for exciting said field winding and having a plurality of field windings respectively energized in accordance with the main machine load and with the motor-generator load.

14. In a system of control, the combina-

tion with a supply circuit and a main dynamo-electric machine having an armature and 20 a field winding, of a plurality of auxiliary mechanically-connected armature windings respectively adapted for driving purposes and to excite said field winding, and a plurality of field windings for the driving auxiliary armature winding respectively energized in accordance with the main machine load and with the driving-auxiliary-armature load.

In testimony whereof, we have hereunto 30 subscribed our names this 29th day of April, 1916.
